UNITED STATES PATENT OFFICE.

PHILIP M. ENGELHARDT, OF CARTERSVILLE, IOWA.

DESIGN FOR A PACKAGE-TIE.

48,273.

Specification for Design.

Patented Dec. 14, 1915.

Application filed February 20, 1915. Serial No. 9,730. Term of patent 14 years.

To all whom it may concern:

Be it known that I, PHILIP M. ENGELHARDT, a citizen of the United States, residing at Cartersville, in the county of Cerro Gordo and State of Iowa, have invented a new, original, and ornamental Design for Package-Ties, of which the following is a specification, reference being had to the accompanying drawing, forming a part thereof.

The figure is a plan view of a package tie, showing my new design.

I claim:

The ornamental design for a package tie, as shown.

PHILIP M. ENGELHARDT.

Witnesses:

T. R. EVANS,
T. F. FLEMING.
